DRY CELL

Frederick A. Keller, New York, N. Y., assignor
to Henry Hyman, Brooklyn, N. Y.

Application December 21, 1935, Serial No. 55,550

3 Claims. (Cl. 136—133)

This invention relates to a dry cell which may be made so as to have a metal cup or casing as one electrode or terminal and a rod of conducting material, such as carbon, for example, constituting the other electrode or terminal.

It is well known that with dry cells of this character there is danger of the cells becoming short circuited by a piece of conducting material becoming inadvertently placed in contact with the center contacting pole and the rim or edge of the metal cup or casing. By the present invention the danger of short circuits being inadvertently caused in this way, by other cells or other pieces of contacting material having substantially straight or slightly curved edges, is avoided.

The invention will be understood from the description in connection with the accompanying drawing, in which Fig. 1 is a side view partly in vertical section through an illustrative embodiment of the invention and Fig. 2, is an end view of the same.

In the drawing, reference character 1 indicates a casing that is made of metal, such as zinc, for example. The casing may have a sleeve 2 of insulating material therearound as shown in dotted lines. The upper end 3 of the positive pole, which may be made of a carbon rod, for example, is shown in section. The upper surface of the sealing wax, or the like, which prevents the electrolyte from escaping, is indicated by the reference character 4. A metal cap 5 is pressed upon the upper end of the electrode 3 in the usual way to form the positive terminal. This cap has an outwardly extending flange 6. A disc 7 of insulating material is provided with a central hole 8 that fits the cap 5 and this disc rests upon the flange 6.

A metal ring 9 has an opening 10 therethrough which is large enough to leave an annular space 11 around the cap 5 when the ring 9 is in place. The annular downwardly extending flange 12 of the ring 9 which defines the outer periphery of the opening 10 has its edge resting upon the upper surface of the disc 7. The diameter of the flange 6 of the cap 5 is preferably slightly larger than the diameter of the annular flange 12 of the ring 9.

The outer annular flange 13 of the ring 9 extends downwardly below the disc 7 and the inside surface of this flange fits the outer periphery of this disc.

The flange 13 terminates in an outwardly extending horizontally disposed annular lip 14.

The washer 15, of stiff insulating material, hav-

ing an opening large enough to accommodate the main portion of the ring 9, rests upon the lip 14 and its outer periphery fits in the inside of the casing 1.

An internal annular rib 16 is pressed in the casing 1 below the washer 15 and the upper edge of the casing 1 is rolled over onto the upper side of this washer 15, as indicated at 17.

The upstanding annular portion of the ring 9 is sufficiently high to prevent electrical connection being made between the rim 17 and cap 5 by a straight piece of conducting material, as this portion of the ring 9 will operate as a fulcrum to prevent such a piece of conducting material from simultaneously touching the rim 17 and cap 5 and thus short circuiting the cell. The ring 9 may be made of metal or other stiff or rigid material that has enough strength to serve the purpose.

The ring 9 cannot shift laterally as its flange 13 fits around the edge of the disc 7 and the opening 8 in this disc fits the cap 5, which, in turn, is frictionally pressed upon the end of the rod 3.

I claim:

1. In a dry cell, a metal casing forming one electrode, a rod of conducting material in said casing, a metal cap on said rod having an outwardly extending flange, a flat washer of insulating material on the top side of said flange, and an annular metallic member on said washer extending above straight lines from said cap to the end of said casing and having a flange along its outer edge and inside of said casing, the inner side of said flange contacting with the outer edge of said flat washer, and a washer of insulating material held between said last named flange and said casing with its inner edge contacting with the outer side of said flange.

2. In a dry cell, a metal casing forming one electrode, a rod of conducting material in said casing forming the other electrode, a metal cap on the end of said rod having a flange, a washer of insulating material supported on said flange, an annular metal member having two flanges of different lengths, the shorter one of which rests upon the upper surface of said washer and the longer one has an out-turned lip, and a larger washer supported by said lip and the upper end of said casing.

3. In a dry cell, a casing, a flanged cap at the end of the center contact of said cell, a plurality of annular members consisting of two insulating members and an intermediate metal member of successively larger outside diameters and inside

diameters having the inside diameter of each smaller than the outside diameter of the preceding one, said annular members being located and assembled so as to rest one upon the other in sequence between the upper end of said casing and said cap, the inner edge of each of said members overlapping a portion of the preceding member,

said metal member extending above straight lines from said cap to the upper end of said casing and having a downwardly and outwardly extending portion between said insulating members and contacting with the edges thereof.

FREDERICK A. KELLER.
